(57) **CLAIM**

The ornamental design for a swimming pool water level regulator, as shown and described.

DESCRIPTION

FIG. 1 is a front, left, top perspective view of a swimming pool water level regulator, showing my new design; FIG. 2 is a rear, right, bottom perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view of the enlarged scale thereof; and, FIG. 8 is a bottom plan view of the enlarged scale thereof. The dashed broken lines in the figures illustrate portions of the swimming pool water level regulator that form no part of the claimed design. The short-short-long dashed broken lines immediately adjacent to the claimed areas in the views represent the boundaries of the design and form no part of the claimed design.
